[57] CLAIM

The ornamental design for a shampoo bowl shower head, as shown and described.

DESCRIPTION

FIG. 1 is a front isometric view of a shampoo bowl shower head according to the invention wherein the dotted lines indicate functional elements which do not form a part of the invention;

FIG. 2 is a first side view of the shampoo bowl shower head wherein the dotted lines indicate a converging water spray pattern produced by the shampoo bowl shower head and does not form a part of the invention;

FIG. 3 is a front view of the shampoo bowl shower head wherein the dotted lines indicate functional elements which do not form a part of the invention;

FIG. 4 is a second side view of the shampoo bowl shower head; and,

FIG. 5 is a back view of the shampoo bowl shower head.
